CLAIM

The ornamental design for a bicycle rack, as shown and described.

DESCRIPTION

FIG. 1 is a perspective view of a bicycle rack, showing our new design;

FIG. 2 is a front elevational view thereof, the rear view being a mirror image of that shown; and,

FIG. 3 is a right side elevational view thereof, the left side being a mirror image of that shown.

FIG. 1

FIG. 2

FIG. 3
